United States Patent Office

Des. 217,518
Patented May 5, 1970

217,518

PORTABLE COOKING STOVE OR SIMILAR ARTICLE

William Rakocy, Clifton, N.J., assignor to Ronson Corporation, Woodbridge, N.J., a corporation of New Jersey

Original design application Sept. 11, 1967, Ser. No. 8,554, now Patent No. 212,178, dated Sept. 3, 1968. Divided and this application Apr. 18, 1968, Ser. No. 12,670

Term of patent 14 years

Int. Cl. D7—04
U.S. Cl. D81—10

This application is a division of my copending application, Ser. No. D. 8,554, filed Sept. 11, 1967, now Pat. No. D. 212,178.

FIG. 1 is a perspective view of a portable cooking stove or similar article showing my new design;

FIG. 2 is a top view thereof;

FIG. 3 is a bottom view thereof;

FIG. 4 is a side view thereof;

FIG. 5 is a front view thereof;

FIG. 6 is a rear view thereof.

I claim:

The ornamental design for a portable cooking stove or similar article, substantially as shown.
